AIR MIXING APPARATUS

Harry A. Whitesel, Glen Ridge, N. J., assignor to
General Electric Company, a corporation of
New York

Application January 26, 1944, Serial No. 519,771

7 Claims. (Cl. 138—42)

My invention relates to air conditioning apparatus and more particularly to apparatus for mixing air in a stream so that the atmospheric conditions thereof are uniform throughout a cross-section of the stream.

In the determination of the performance of air conditioning apparatus it is frequently necessary to know the average temperature or the average humidity of the air in a stream; normally, however, the atmospheric conditions prevailing over the cross-section of a stream of air vary widely so that temperature measured at one point in the cross-section differs from that at another point. It is desirable that a single reading of a thermometer or humidity indicating device be sufficient to determine the average temperature or humidity of the stream. A single reading may be sufficient provided the stream is thoroughly mixed to render the atmospheric conditions uniform throughout the cross-sectional area of the stream. It is desirable that apparatus for testing the performance of an air conditioning system be as compact as possible; and in order to obtain the desired compactness, it is often necessary to provide a change in direction of the stream of air. It is an object of my invention to provide an improved apparatus for thoroughly mixing the air in a stream to render uniform the atmospheric conditions throughout a cross-section of the stream.

It is another object of my invention to provide a compact and efficient apparatus for thoroughly mixing the air in a stream to render the atmospheric conditions thereof uniform throughout a cross-section of the stream and including an improved arrangement for changing the direction of the stream during the air mixing operation.

Further objects and advantages of my invention will become apparent as the following description proceeds, and the features of novelty which characterize my invention will be pointed out with particularity in the claims annexed to and forming part of this specification.

For a better understanding of my invention reference may be had to the accompanying drawing in which Fig. 1 is a sectional elevation view of a calorimeter for testing heat exchange units and including air mixers embodying my invention; Fig. 2 is an enlarged perspective view of the air mixing apparatus shown in Fig. 1 with the top wall and side removed to show the interior of the mixer; and Fig. 3 is a curve representing the operating characteristics of the air mixing apparatus.

Referring now to the drawing, Fig. 1 illustrates a calorimeter comprising a thermally insulated cabinet 10 including a compartment 11 in which is arranged a heat exchanger 12 to be tested, a compartment 13 containing an air circulating fan 14, heat exchange apparatus 15 and humidifying apparatus 16. A middle compartment 17 is provided between the compartments 11 and 13 and may contain the connections (not shown) to the heat exchange apparatus for conducting heat exchange fluid to the apparatus in the other compartments. Communication between the compartments 11 and 13 is provided at one end by an air mixing apparatus 18 and at the other end by a similar apparatus 21. The cabinet 10 is, of course, provided with doors providing access to the several compartments of the cabinet. These doors have not been shown as they are not necessary to an understanding of the invention. The calorimeter provides an arrangement whereby air may be circulated over the unit 12 which is to be tested and may then be returned to the compartment 13 where its temperature and humidity are restored to their values before passing over the unit 12. During the operation of the apparatus illustrated, the unit 12 is supplied with heating or cooling fluid at a predetermined temperature and air is circulated through the cabinet by operation of the fan 14. The air leaving the fan 14 passes through the mixing device 21 and is discharged from the device into the cabinet 11, the air in the stream discharged from the device 21 being of uniform condition throughout its cross-sectional area so that a thermometer or other temperature measuring device 22 and a relative humidity measuring device 23 may be placed at the outlet of the apparatus 21 to determine the average temperature and average relative humidity of the air supplied to the heat exchanger 12. After the air is passed over the unit 12, it enters the mixing apparatus 20 and is discharged therefrom into the compartment 13, the average temperature and humidity of the air discharged to the compartment 13 being uniform throughout the cross-section of the discharge outlet so that a thermometer or temperature measuring device 25 and a relative humidity measuring device 26 may be employed to determine the average temperature and relative humidity of the air as a result of its having passed over the heat exchange unit 12. This air then passes over the heat exchanger 15 where it is either heated or cooled and over the humidifying apparatus 16 so that the air returned to

the fan 14 is restored to a predetermined condition before its recirculation to the compartment 11. The calorimeter thus comprises an apparatus for circulating air in a closed path under conditions such that it is supplied to the heat exchange unit to be tested at known temperature and relative humidity and so that the performance of the heat exchange apparatus may be measured.

The details of the construction of the air mixers 20 and 21 are shown in Fig. 2. Both the mixers 20 and 21 are of the same construction. Fig. 2 may be considered as a view of the mixer 21 since its inlet and outlet correspond in position to those of the mixer 21. The mixer as illustrated comprises a rectangular frame work constructed of angle iron members 27, and is provided with an inlet over which is secured a foraminous plate or screen 28 and an outlet over which is secured a similar screen 29, the mixer being completely closed except for the inlet and outlet. The screens 28 and 29 and the several walls of the apparatus are secured to the angle iron members 27 to form a rectangular box-like duct structure. These screens serve to make the velocity of the air uniform over the cross-sectional area at the inlet and outlet of the device. The mixer is divided into three compartments by solid partitions 30 and 31, the lower compartment, indicated at 32, being the inlet compartment, the upper compartment 33, the outlet compartment, and the intermediate compartment 34 being formed between the inlet and outlet compartments. The front side of the intermediate compartment 34 is closed by a wall 35 between the screens 28 and 29. Communication between the compartments 32 and 34 is afforded by an opening 36 formed at the rear of the partition 30 remote from the inlet and between the partition and the side and rear walls of the mixer. Communication between the compartment 34 and the outlet compartment 33 is afforded by an opening 37 in the partition 31 between the rear wall and the other side wall of the mixer. An upright baffle or partition member 38 is provided so that it extends transversely between the partitions 30 and 31 and prevents direct passage of air between the openings 36 and 37, the partition 38 dividing the compartment 34 into two sections maintained in communication through an opening 39 formed between the partition 38 and the front wall 35 of the mixer. It will thus be evident that the air stream passing through the inlet screen 28 is directed in a tortuous path through the three compartments of the mixer. A mixing apparatus of this general type but which does not provide a reversal of the direction of the air between the inlet and the outlet is described and claimed in my copending application, Serial No. 511,270, filed November 22, 1943, and assigned to the same assignee as my present invention.

I have found that by making the openings 36, 37 and 39 of a cross-sectional area less than one-half of the cross-sectional area of the inlet 28, and preferably of the order of one-third the area of the inlet, the air stream passing through the apparatus is thoroughly mixed. This thorough mixing is further facilitated by making the compartment 34 of smaller cross-section and volume than the compartments 32 and 33 so that the air in passing from the inlet compartment to the compartment 34 is reduced in average cross-section and is correspondingly increased in average cross-section on passing into the outlet com-

partment 33. The inlets and outlets are preferably of the same cross-sectional area. The mixing apparatus is preferably rectangular in form and the cross-sections of the compartments and the openings are also preferably rectangular, and the inlet and outlet openings between the compartments are also rectangular.

An apparatus constructed as shown in Fig. 2, when tested, provided thorough mixing of the air, as is illustrated by curves of the graph of Fig. 3. Fig. 3 represents the temperatures prevailing in eighteen positions over the inlet and outlet of the apparatus shown in Fig. 2, the curve 40 indicating the temperatures prevailing at the inlet and a curve 41 the temperatures at corresponding positions at the outlet. Each curve is broken into three parts connected by dotted lines and each part comprises six temperature readings in top, middle and bottom rows, respectively, of the inlet and outlet openings. It is readily apparent that the temperatures at the inlet, as indicated by the curve 40, vary widely whereas the temperatures over the cross-sectional area at the outlet are substantially constant. It is readily apparent from Fig. 3 that the possibility of error due to measuring the temperature at a single point in order to determine the average temperature has been minimized.

The dimensions of the air mixing apparatus illustrated in Fig. 2 are selected so that no undue pressure drop will exist in the calorimeter and are selected in accordance with the capacity of the fan 14.

From the foregoing it is readily apparent that I have provided a simple and easily constructed arrangement which makes it possible to mix thoroughly the stream of air passing through a duct and, furthermore, is such that the direction of the stream of air may be reversed, this construction lending itself particularly to closed circuit apparatus such as the calorimeter illustrated.

While I have described my invention in connection with a calorimeter for determining the performance of heat exchange apparatus, other applications will readily be apparent to those skilled in the art. I do not, therefore, desire my invention to be limited to the particular construction illustrated and described, and I intend by the appended claims to cover all modifications which fall within the spirit and scope of my invention.

What I claim as new and desire to secure by Letters Patent of the United States is:

1. An apparatus for effecting thorough mixing of the air in a stream to provide uniform atmospheric conditions throughout a cross-section of the stream comprising a duct structure having an inlet and an outlet, partitions arranged in the duct for dividing said duct into two end compartments communicating respectively with said inlet and said outlet and a third compartment between said end compartments, said partitions being arranged to provide openings between said end compartments and said third compartment remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, all of said openings being of substantially the same size and each hav-

ing an area less than one-half the area of said inlet.

2. An apparatus for effecting thorough mixing of the air in a stream to provide uniform atmospheric conditions throughout a cross-section of the stream comprising a rectangular duct structure having a rectangular inlet and a rectangular outlet, partitions arranged in the duct for dividing said duct into two rectangular end compartments communicating with said inlet and said outlet and a third rectangular compartment between said end compartments, said partitions being arranged to provide rectangular openings between said end compartments and said third compartment remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, all of said openings being of substantially the same size and each having an area of the order of one-third that of said inlet.

3. An apparatus for effecting thorough mixing of the air in a stream to provide uniform atmospheric conditions throughout a cross-section of the stream comprising a rectangular duct structure having a rectangular inlet and a rectangular outlet in the same wall thereof, partitions arranged in the duct for dividing said duct into two rectangular end compartments communicating with said inlet and said outlet and a third rectangular compartment between said end compartments, said partitions being arranged to provide rectangular openings between said end compartments and said third compartment remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, all of said openings being of substantially the same size and each having an area less than one-half the area of said inlet.

4. An apparatus for effecting thorough mixing of the air in a stream to provide uniform atmospheric conditions throughout a cross-section of the stream comprising a duct structure having an inlet and an outlet, partitions arranged in the duct for dividing said duct into two end compartments communicating respectively with said inlet and said outlet and a third compartment between said end compartments, said third compartment having a volume substantially less than the volume of one of said end compartments, said partitions being arranged to provide openings between said end compartments and said third compartment remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, all of said openings being of substantially the same size and each having an area less than one-half the area of said inlet whereby the cross-sectional area of the

stream passing through said duct is reduced on passing from said inlet to said third compartment and is increased upon passing from said third compartment toward said outlet.

5 5. An apparatus for effecting thorough mixing of the air in a stream to provide uniform atmospheric conditions throughout a cross-section of the stream comprising a rectangular duct structure having an inlet and an outlet in the
10 same side wall thereof, partitions arranged in the duct for dividing said duct into two rectangular end compartments communicating respectively with said inlet and said outlet, and a third rectangular compartment between said end compartments, said third compartment having a volume substantially less than the volume of either of said end compartments, said partitions being arranged to provide rectangular openings between said end compartments and said third compartment
15 20 remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, each of said openings having an area less than one-half the area of
25 30 said inlet whereby the cross-sectional area of the stream passing through said duct is reduced on passing from said inlet to said other compartment, and is increased upon passing from said third compartment toward said outlet.

35 6. An apparatus for effecting thorough mixing of the air in a stream to provide uniform atmospheric conditions throughout a cross-section of the stream comprising a duct structure having an inlet and an outlet, partitions arranged in
40 the duct for dividing said duct into two end compartments of substantially the same size communicating respectively with said inlet and said outlet and a third compartment between said end compartments, said third compartment having a cross-sectional area of approximately two-thirds the cross-sectional area of each of said end compartments, said partitions being arranged to provide openings between said end compartments and said third compartment remote from said inlet and said outlet, a baffle in said third compartment extending transversely between said partitions for preventing direct passage of air from one of said openings to the other and dividing said third compartment into two sections having an opening therebetween whereby air passing from said inlet to said outlet is directed through said compartments in a tortuous path, all of said openings and the cross-sectional area of each of said two sections being of substantially the same size and each having an area less than one-half the area of said inlet whereby the cross-sectional area of the stream passing through said duct is reduced on passing from said inlet to said third compartment and is increased upon passing from said third compartment toward said outlet.

7. An apparatus for effecting thorough mixing of the air in a stream to provide uniform atmospheric conditions throughout a cross-section of the stream comprising a rectangular duct structure having a rectangular inlet and a rectangular outlet in the same wall thereof, said inlet and outlet having the same cross-sectional area, partitions arranged in the duct for dividing said duct into two rectangular end compartments communicating with said inlet and said outlet and a

third rectangular compartment between said end compartments, said third compartment having a cross-sectional area approximately two-thirds that of said inlet, said partitions being arranged to provide rectangular openings between said end compartments and said third compartment remote from said inlet and said outlet, a baffle in said third compartment extending transversely between said partitions for preventing direct pas-

sage of air from one of said openings to the other and dividing said third compartment into two sections having an opening therebetween whereby air passing from said inlet to said outlet is directed through said compartments in a tortuous path, all of said openings being of substantially the same size and each having an area substantially one-third the area of said inlet.

HARRY A. WHITESEL.
